UNITED STATES PATENT OFFICE.

HENRY E. NICKERSON, OF BRIDGEPORT, CONNECTICUT, ASSIGNOR, BY MESNE ASSIGNMENTS, TO WEBER ELECTRIC COMPANY, OF SCHENECTADY, NEW YORK, A CORPORATION OF NEW YORK.

LAMP-SOCKET-SECURING MEANS FOR ELECTRIC FIXTURES.

Application filed July 26, 1926. Serial No. 124,960.

The present invention has reference to lighting appliances and pertains more especially to a device for holding an electric lamp socket in position therein.

5 One of the objects of this invention is the production of an improved holding device of the character described, adapted to accommodate the exterior of the metallic casing associated with a lamp-socket, preferably of the 10 usual type, and locking the same to the interior of an existing, so-called ceiling canopy, still without changing the latter or the socket.

Another object is the provision in a holder 15 of the type specified, of retainers capable of engaging either or both of the side and end portions of an electric lamp socket, for the purpose of keeping the latter from axial displacement.

A further object consists in producing a 20 device of the class set forth, embodying means for positively locating the exit for the pulling medium of what is termed a "pull-socket," in alignment with the passage for this medium in the side of the ceiling canopy.

25 Still another object resides in providing a device of the nature referred to, having means coacting with a projection upon a lamp socket, preferably at the side thereof; and also having means to exert a thrust against 30 one side of an interior part belonging to the canopy, and serving to draw the opposite portion of the socket onto the other side of the same part.

A still further object is the production of 35 a device of the kind mentioned, arranged to support the casing of a standard lamp socket upon an interior ledge usually formed at the juncture between the parts constituting the canopy, irrespective of the size of the opening left intermediate the edges of this ledge.

An additional object is to provide a device 40 for the purpose implied, in the use whereof certain parts of a lamp socket unaffected by the operation of the latter, may be advantageously omitted to reduce the cost of the ensemble.

45 A general object is to furnish a practical device of the genus alluded to, composed of few and simple parts; of light but strong and durable construction; reliable as well as convenient to assemble; besides amenable to low cost of manufacture, principally through punch-press operations.

50 Other objects and advantages of the inven-

tion will become apparent as the specification proceeds.

With the aforesaid objects in view, the invention consists of the novel combinations and arrangements of parts hereinafter described in their preferred embodiments, 60 pointed out in the subjoined claims, and illustrated on the annexed drawing, wherein like parts are designated by the same reference characters throughout the several views.

Generally described, the device under consideration includes in its organization, a flange-like support having an interior rim which affords a seat for the customary enlarged middle portion of the metallic casing that envelopes the lamp-socket proper. The 70 underside of this support rests upon the upper face of an inwardly extending annular ledge usually formed at the juncture of the top and bottom shells composing a ceiling canopy. A flanged nut is employed to engage screw threads embodied with the lower portion of the socket casing. The flange of the aforesaid nut when same is tightened up, bears against the under face of the ledge mentioned and serves to clamp the socket casing 75 and its support thereto. Retaining means rising from and suitably fixed relative to the flange-like support is provided for the purpose of engaging a side or lateral projection on the socket, such as the guide-throat for the 80 pull-chain which projects from the side of the lamp-socket. Another means may be provided on the support, if desired, to reach over the end of the socket with the object of anchoring it to the flanged support. Coacting 85 receiving and engaging elements incorporated with the support and the annular ledge, respectively, are adapted to locate the before named guide-throat in proper relation to a passage for the pull-chain through the 90 side of the canopy.

The advantages of the invention as here outlined are best realized when all of its features and instrumentalities are combined in the one and same structure, but, useful devices may be produced embodying less than 95 the whole.

It will be obvious to those skilled in the art to which the invention appertains, upon becoming conversant with the details thereof, 100 that the same may be incorporated in several different constructions. The accompanying drawing, therefore, is submitted merely as

showing the preferred exemplification of the invention.

In the said drawing:—

Figure I is a sectional elevation of this improved holding device, parts thereof being broken away;

Fig. II is a perspective view of a supporting member pertaining to the invention;

Fig. III is a fragmentary sectional elevation showing a modified construction of locking element operatively connected up with the supporting member illustrated by Fig. II; and

Fig. IV is a perspective detail view of a retainer employed in conjunction with the structure represented by Fig. I.

Referring now to these views of the annexed drawing, for a detailed description of the invention thereby exemplified, it will be noted that capital letters are employed to designate the known parts pertaining to a ceiling canopy and lamp-socket, and the same as used herein, are meant to indicate as well other structures to which this improved device is applicable, that is, such entities as are not deemed to belong to the present improvements, except in so far as they form there-with legitimate combinations of elements capable of yielding novel and useful results. On the other hand, the elements and members identified with said improvements, are denoted by reference numerals in the approved manner.

Pursuant therefore, to the mode of notation herein adopted, A represents the upper, inverted shell of a ceiling canopy that is joined to a lower inverted shell B, by the usual method of sealed flanges, C, D and E. Of these flanges, C constitutes the continuation of the bottom edge of the first mentioned shell, while the other flanges D and E, which take respectively over and under the intermediate flange C, are formed with the top edge of the lower shell B. The before named flanges, comprising together an annular ledge F which extends a certain distance inwardly of the canopy shells A, B, thus leaving a central opening G therethrough. Piercing the lower margin of the shell B, are screws one of which is denoted at H, and whereon is carried by its rim, in the ordinary manner, a shade J of any approved shape and design. K designates the metallic casing that surrounds the customary electric lamp-socket and which is shown as having at the side thereof a projection which in the type of socket illustrated is a guide-throat L, for the pull-chain M, operating its current control, as is common practice. This pulling medium is led outwardly through the side of the upper canopy shell by means of a passage N provided therein. The socket-casing K is of the usual type having a reduced lower portion forming external casing portions of different diameters and is furnished exteriorly at the lower por-

tion thereof, as usually is the case, with suitable means such as the screw-threads P for attaching a fastening device. An electric light bulb, depending from the interior of the lamp-socket, is denoted at Q.

Removably inserted from the top of the upper canopy shell A, and lodged upon the ledge F thereof, is a flange-like member 11, spanning the edges that bound the central opening G. This member may be either placed in direct contact with said ledge F, or one or more spacing washers 13 of suitable material, can be interposed between the underside of the member's flange (11) and the top face of the said ledge, in order to maintain the member at a desired elevation relative to the ledge mentioned. For purposes of preventing rotation of the member 11 with respect to the ledge F, or in other words, to locate the said member in a predetermined position thereto, the flange portion (11) may be provided with a receiving element 15 offset to one side of the flange, that is, upwardly as shown on the accompanying drawing. With the said element 15 coacts an engagement element 17, raised above the upper surface of the annular ledge F. While two receiving elements have been indicated in Fig. I, one by full lines in front, and the other dotted, at the rear of the socket-casing K, it is within the province of the invention to employ only a single one of these elements, as depicted at 15^a, Fig. II. Furthermore, it will be understood, that the aforesigned receiving and engaging elements 15 and 17 respectively, may be reversely disposed from what has been specifically illustrated.

Spaced inwardly of the outer edge of the member 11 and elevated above the flange portion thereof, is an interior rim 19, constituting a seat with which coacts the bulging middle part of the lamp-socket casing. The lower contracted portion of the latter depends below the flange (11) of the said member and the ledge F sublying the same. By reason of the fact that the external diameter of the member's flange is of smaller size than the largest dimension of the similar portion of the said ledge, and also that opening G in the canopy, is wider than the measurement across the contracted lower part of the socket casing, the flange and the casing mentioned, may be shifted laterally to a limited extent, while the before named elements 15, 17, still are in engagement one with the other.

The means for keeping the lamp socket in position relatively to the flanged member and prevent disassociation therebetween, consists as shown, of a yoke-shaped retainer 21, preferably made of resilient material. As seen most clearly in Fig. IV, this yoke comprises legs 23, extending from the transverse sides of a bridge or cross-piece 25, of slightly dished formation. From Fig. I it will be observed, that the cross-piece referred to,

overlies the upper extremity of the casing proper, i. e. after the cap generally taking over the same, has been removed. The width of the bridge-piece 25 may be such as to wholly or partly cover the top of the casing K. Between the underside of the yoke's bridge and the top of the interior of the socket casing, is interposed a disc 27, of an appropriate insulating substance. Although it has been illustrated that the said cross-piece 25 and the legs 23, are composed of strap-like material of uniform width, it will be comprehended that this can be varied to suit conditions encountered in practice, e. g. one or the other of these parts may be wider or narrower, as desired. At 29 is indicated that the legs 23 are forked and that the extremities of these bifurcations are bent or offset inwardly, feet-like, under the bridge 25, as denoted at 31. The purpose of the bifurcated legs, is to straddle a projection on the socket which in the present instance is the guide-throat L, ordinarily projecting from the side of certain types of lamp-sockets. Subsequently to pushing the branched legs 23 over the sides of the socket casing, the offsets or feet 31, snap beneath the under faces of the raised portions pertaining to the receiving elements 15, on opposite sides of the flanged member 11. Flexing of the bridge or cross-piece 25 enables the aforesaid feet to effect the engagement spoken of. For casings void of chain guide-throats or other projections in their sides, there is no necessity of making the legs 23 of the retainers 21 of forked formation.

Under certain circumstances where it is desired to have an additional safeguard so as not to depend upon the yoke 21 alone, to hold the lamp-socket casing onto its seat 19 in the member 11, an arm 33 is provided, which arm projects upwardly from the edge of the flanged portion of the said member. The upper terminal of this arm is by preference bent right angularly over the top of the socket casing, on the order of a finger, as indicated at 35, Figs. I and II. Adjacent to its free end, the aforementioned finger is threaded for a screw 37, that is disposed in eccentric relation to the axis of the said socket, with the object of more effectively precluding rotation of the latter with respect to its seat 19. Notwithstanding only one screw 37 has been shown, it stands to reason, that any number thereof can be employed to exert an endwise bearing pressure upon the socket in question. It is also conceivable that one of the screws may be entered through a tap hole 39 in the arm 33 so as to impinge laterally on the socket casing K.

At 41 is represented a sleeve-like, flanged nut which is adapted to engage the threads P or equivalent attachment part formed with the lamp socket casing, that is, on the exterior of the latter's contracted outer portion.

It will be perceived that while the flange part 43 of this nut reaches upwardly outward from the lower side of the sleeve portion (41) thereof, the flange referred to, may equally as well, extend up from the top of this sleeve. 70

The uppermost edge of the flange 43, when the same is screwed up tight, is in abutting relation with the underface of the hereinbefore mentioned ledge F. The downward stress imposed upon the socket-casing K by tightening of the nut 41, not only draws the said casing in firm contact with the member 11, but serves also to anchor the latter to the aforesigned ledge. Openings 45 provided at the juncture of the flange 43 with the sleeve (41) are designed to accommodate a pin wrench (not shown) wherewith the anchoring nut is screwed into or out of its assigned position, as the case may be. 80

From the foregoing it will be observed, 85 that the nut 41 secures the member 11, which in fact constitutes an abutment appendage on the socket casing K, to the supporting ledge F. The yoke 21 and the finger 35, both operate to retain the parts within the casing K 90 from being pushed out therefrom when the lamp Q is inserted into the same, and, the receiving and engagement elements 15 and 17 respectively, locate the member 11 and the therewith indirectly connected guide-throat L in proper position relatively to the exit N for the pull-chain M in the canopy shell A. 95

In instances where a socket casing is used having no screw threads at the contracted portion thereof, the arrangement depicted by Figs. II and III, for anchoring the abutment member 11^a to the ledge support F, may conveniently be employed. The flange portion of this member is provided with tapped apertures 47, which as seen to best advantage in Fig. II, are centrally disposed within recesses 49 formed in the side of the raised seat 19 of the said member. Into the aforesaid apertures are threaded screws, whereof one is indicated at 51, Fig. III, which screws pass through the body of a washer 53. The latter's central clearance opening takes over the contracted end of the unthreaded socket casing and abuts with its top face against the underside of the ledge F, at such times as the screws 51 are tightened, thus effecting a firm connection of the member 11^a and the said washer on opposite sides of the aforesigned ledge. 110

While the socket casing retainer 21, has been shown and described as constituting a separate adjunct to the flanged member 11, Fig. II illustrates that the leg 23^a, serving a like purpose to that of the first mentioned leg 23, may be formed integral with and extend upwardly from the edge of the flanged member 11^a. Bifurcations 29^a, provided on the said leg 23^a, enables the same to yield far enough, to permit of the lateral projection or guide throat L, being forced down be- 120 125 130

tween them. It will be noted that each portion of the bifurcation is cut away or formed to provide a suitable retaining formation, which upon receiving the projection or throat 5 L, is adapted to restrain the socket against upward movement relative to the flange member 11^a, as well as against rotation therein. The construction last referred to, will be found especially handy, when it is desired 10 to keep the usual cap over or in position on the socket casing. Fig. II illustrates in addition, that the finger 35 offset from the arm 33, is provided with spaced apart prongs 55 capable of taking around the neck wherewith 15 some casing caps, as well known, are commonly supplied.

In view of what has been hereinbefore stated, it will be readily seen, that the device in question, is not only of simple construction and therefore of low cost to manufacture, but also that the parts comprising the same can be quickly and readily joined together. The use thereof affords a reduction in the price of the standard lamp socket, as its cap 20 can be omitted without detriment or inconvenience. It is an easy matter to place the socket casing K in the seat of the flanged member 11, apply the retaining yoke 21 over the casing for engagement with the receiving element 15, and set the latter upon the coacting element 17, with the flange of the member in contact with the ledge F. Affixing of the nut 41 completes the assembling 25 which can be performed by any person of average intellect although inexperienced. The procedure above set forth, is substantially the same when the member 11^a and the screw-held washer 53 is used. The retainer arms 23^a and 33 possesses sufficient elasticity 30 to admit of being forced open or back during insertion of the socket casing, and subsequently snapping or closing thereover.

While certain preferred embodiments of this device have been shown and described, it 45 will be understood that changes in the form, arrangements, proportions, sizes and details thereof may be made, without departing from the scope of the invention as defined by the appended claims.

Having described my invention what I 50 desire to secure by Letters Patent and claim, is:

1. In a lighting fixture including a flange-like support, the combination with an electric lamp-socket including a casing having screw threads thereon, of a member separate from said casing constituting a holder therefor seated on said support, a nut independent 55 of said socket engageable with said threads and provided with a part abutting the support, and means coacting with said member arranged to take over a portion of the socket to retain the interior thereof from being displaced.

2. A device of the class described compris-

ing an annulus adapted to receive therein an electric lamp socket having a shell and a lateral projection from the interior parts thereof, said annulus having an upwardly extending arm having an engaging portion 70 adapted to engage said projection upon the socket and serve to restrain the socket against movement out of said annulus.

3. A socket assembly unit, for use with a lighting canopy or the like having an internally projecting flange, comprising a socket having a shell, and a lateral projection from the interior parts thereof, an annulus on said shell receiving the same, said shell having an enlarged portion limiting movement through 75 the annulus in one direction, an arm on said annulus extending substantially longitudinally of the shell and engaging said lateral projection, whereby to resist movement of the socket in the other direction relative to said annulus, and means associated with said socket and annulus for clamping the latter upon the internal flange of a canopy. 80

4. A socket assembly unit for use with a lighting canopy or the like having an internally projecting flange, comprising a socket having a shell, and a lateral projection from the interior parts thereof, an annulus on said shell receiving the same, said shell having an enlarged portion limiting movement through 85 the annulus in one direction, an integral portion on said annulus extending along the shell and engaging said lateral projection, whereby to resist movement of the socket in the other direction relative to said annulus, and a collar 90 threaded on said socket adapted to cooperate with said annulus to clamp the internal flange of a canopy therebetween.

5. In combination with a lighting fixture having an internal flange, an electric lamp 95 socket having the usual shell with portions of different external diameters and a lateral projection from the interior parts thereof, an annulus receiving said socket and permitting only partial movement of the socket there- 100 through, in one direction, said annulus resting upon the top of said flange and having a portion engaging said projection to restrain the socket against movement in the other direction out of the annulus, and detachable 105 means at the opposite side of said flange for anchoring the annulus in position.

6. In combination with a lighting fixture having an internal flange, an electric lamp 110 socket having the usual shell with portions of different external diameters, and a lateral projection from the interior parts thereof, a ring-like member receiving said socket resting against said flange and having an up- 115 standing portion engaging said projection to restrain the socket parts against movement in one direction away from the member, said shell having a portion limiting movement 120 of the socket through said member in the other direction, and a collar around the socket 125 130

at the opposite side of said flange for anchoring the member in position.

7. In combination with a lighting fixture having an internal flange, an electric lamp socket having the usual shell with portions of different external diameters, an annulus resting on said flange and receiving said socket, an arm on said annulus extending longitudinally of the socket and having a portion engaging the socket to resist movement thereof

out of the annulus in one direction, the annulus itself limiting movement of the socket therethrough in the other direction, and a member formed separate from the annulus surrounding the socket at the opposite side 15 of said internal flange over the canopy and serving with the annulus to clamp the flange therebetween and thereby to anchor the annulus and socket in position on the flange.

HENRY E. NICKERSON.
